Primary Examiner — Elizabeth A. Albert(74) *Attorney, Agent, or Firm* — Leason Ellis LLP(57) **CLAIM**

The ornamental design for an alignment tool, as shown and described.

DESCRIPTION

FIG. 1 is a perspective view of an alignment tool according to our new design;

FIG. 2 is a front view thereof;

FIG. 3 is a rear view thereof;

FIG. 4 is a right, side view thereof;

FIG. 5 is a left, side view thereof;

FIG. 6 is a top plan view thereof; and,

FIG. 7 is a bottom plan view thereof.

The broken-line showing of portions of the tool is included for the purpose of illustrating environmental structure and forms no part of the claimed design.
